TRACK FOR TRACK LAYING WHEELS

Joseph Kuchar, Chicago, Ill., assignor to Forged-Trak Co., Chicago, Ill., a corporation of Delaware

Application May 6, 1932, Serial No. 609,605

7 Claims. (Cl. 305—10)

This invention relates to tracks for track laying wheels which are adapted to be laid on the ground to provide support for a vehicle, and to be raised continuously as the vehicle proceeds.

5 The invention particularly relates to tracks comprising a series of articulated track elements, adjacent track elements being adapted to be trussed one to the other so as to provide a beam or bridge which is rigid against displacement in one direction and which is flexible with respect to displacement in the opposite direction.

One of the objects of the invention is to provide an improved track.

15 A further object of the invention is to provide an improved track element.

A further object of the invention is to provide a track built of a plurality of elements, those most subject to wear being readily removable and replaceable.

20 A further object of the invention is to provide a track having an improved truss mechanism.

Other objects, advantages and capabilities of the invention will hereinafter appear in the following description of a preferred embodiment thereof, taken in conjunction with the accompanying drawings, in which—

Figure 1 is a side elevation of a truss wheel embodying my invention;

Fig. 2 is a fragmentary cross-sectional view on a larger scale, taken on the line 2—2 of Fig. 1;

Fig. 3 is a plan view of the track, partly in section taken on the line 3—3 of Fig. 4;

Fig. 4 is a side elevation of a portion of the track, showing the construction thereof in greater detail than is shown in Fig. 1, and on a larger scale;

Fig. 5 is a plan view of one of the link elements;

Fig. 6 is a plan view of one of the truss elements;

40 Fig. 7 is a side elevation thereof;

Fig. 8 is a sectional view taken therethrough on the line 8—8 of Fig. 6;

Fig. 9 is a plan view of a modified form of truss element, and

45 Fig. 10 is a side elevation thereof.

Referring to the drawings, the improved track 10 is shown as part of a truss wheel. This truss wheel comprises a beam 11 which is pivotally mounted on an axle 12 at its center. At either end the beam 11 carries bearings 13 for axles 14 which project outwardly from the beam at either side. Wheels 15 are keyed to the axle 14 at each end. The peripheries of the wheels 15 are adapted to engage with portions of the track, which

provide a rail or support for said wheels in the manner hereinafter more fully described.

The track 10 is constituted by a continuous series of articulated elements 16 which are pivotally connected together so that the same may accommodate themselves around the wheels 15 in the manner shown in Fig. 1. Means are provided so that each track element may interlock with the adjacent track elements in such a manner that the track is rigid when subjected to load 10 in one direction and is flexible and readily bent in the other direction. The rigidity referred to is important in the portion of the track located below and between the two pairs of wheels 15, this portion acting as an inverted bridge and distributing over a large area the load applied by the axle 12 on the beam 11.

Each track element comprises a shoe plate 17 which may be formed of forged steel, rolled steel or other suitable material. Each plate 17 may 20 be provided with transverse grousers or ribs 18. At its forward and rearward edges the plate 17 is provided with curved surfaces which cooperate with complementary surfaces upon the adjacent shoe plates in the manner shown in Figs. 25 1 and 4. On each side each shoe plate 17 has secured thereto a link element 19 which will now be described. The link element 19 preferably is a forging of the structure in configuration shown in Figs. 1 to 5 inclusive. The link element 30 19 is provided with hubs 20, 21 which are staggered transversely in the longitudinal direction so that the outer face of the hub 20 is in substantial longitudinal alignment with the inner face of the hub 21, as will more readily be understood with reference to Fig. 3. The hubs 20 and 21 are connected by a sloping vertical web 22 which is provided at its lower edge with a horizontal web 23 and at its upper edge with a horizontal web 24. The base web 23 is provided on 35 its upper side with bosses 25 which are provided with openings whereby the link element may be secured to the shoe plate 17 by means of bolts 26.

The upper surface of the web 24 is machined to provide a flat face 27. As will hereinafter appear, the flat faces 27 of the aligned links provide a track or rail for the wheels 15, which track or rail is laid down in front of the wheels and is taken up after the last wheels have passed over it. On the inner side of the surface 27 the link element 19 is provided with an upwardly extending arm 28, which may suitably be a web of substantially triangular appearance. The arm 28 is provided at its upper end or apex with a hub 29, the axis of which is preferably located 45 50 55

approximately half way between the centers of the hubs 20 and 21 and at a substantial distance thereabove.

It will be understood that the link elements 19 which are secured to opposite sides of the shoe plate 17 are exactly similar, one being a mirror image of the other, so that the hubs 20, 21 and 29 on each link element are in transverse alignment.

10 The hubs 20 of each opposite pair of link elements 19 are connected by sleeves 30 which have a drive fit therein, and extend slightly therebeyond on either side so that in assembled condition said ends project into the hubs 21 which are 15 counterbored to receive them. Pins 31 have a drive fit in the hubs 21 and extend through the sleeves 30 in which they have a working fit.

In assembling the track two opposite link elements 19 are placed on either side of a sleeve or bushing 30 with their hubs 20 in alignment therewith. The link elements are pushed inwardly so as to enter the sleeve 30 into the hubs 20 so as to project therebeyond to the desired extent. A pin 31 is passed through the sleeve 30 and a further 25 pair of opposite links 19 are placed with their hubs 21 in alignment with the pin 31 and with their hubs 20 in alignment with a further sleeve 30. The last said pair of link elements are then 30 pressed home. This assembling operation is continued until a track of the desired length is 35 built up. The link elements 19 may be bolted to the shoe plate 17 at any time after these links are assembled with respect to the sleeve or bushing 30. While it has been indicated that it is 40 preferred to press opposite links 19 upon the pins 31 simultaneously with the pressing of the links upon the sleeve 30, it will be understood that this manner of assembly may be modified. For example, the pins 31 may be pushed from one side 45 of the links 19 after they have been assembled upon the bushings 30.

It will be noted that the sleeve 30 having a drive fit in the hubs 20 secures the opposite links 19 in rigid assembly. The pin 31 having a drive fit in the hubs 21, is rigid with respect thereto. Between the sleeve 30 and the pin 31 there is a 45 working clearance. Consequently the only surfaces subjected to wear owing to the relative movement between adjacent links are the inner surfaces of the sleeves 30 and the outer surfaces of the pins 31 in contact therewith. Owing to the construction described the surfaces are enclosed with respect to sand and dirt and are adapted to retain lubricant supplied thereto in 50 any suitable manner for a considerable time.

In order that the ends of the track may be readily united together and disconnected, for example when applying the track to the wheels 15 or removing it therefrom, I make a sleeve 32 55 at one extremity of the track shorter than the sleeves 30 so that its ends lie flush with the hubs 20 into which it is pressed. The hubs 21 at the other end of the track are provided with the usual counterbores, into which are placed rings 60 33, which occupy the position of the projecting ends of the sleeves 30 in the other pivots of the track. A pin 34 has a free sliding fit through the sleeve 32, the rings 33 and the hubs 21 associated therewith. These hubs 21 are provided 65 on their outer faces with slots so that cotter pins 35 may pass through openings at the extremities of the pin 34 so as to hold said pin in position.

It will readily be understood that the track is assembled by applying the same around the 70 wheels 15. The rings 33 are inserted in the re-

cess or counterbores on the inner sides of the hubs 21. The hubs 20 are then slipped in between the hubs 21 and the pin 34 is slipped into position. The cotter pins 35 are then inserted and the installation is complete.

5 The truss elements are carried by pins 36 which may be driven through the hubs 29 during the assembly operation above described, or at a later time. I have shown one form of truss element in Figs. 1 to 8 inclusive and another form 10 in Figs. 9 and 10. The first form will now be described.

Referring more particularly to Figs. 6, 7 and 8 the truss element is designated by the reference numeral 37 and comprises two side webs 38 which converge forwardly from a sleeve 39, with which they are integral. The sleeve 39 has an opening 40 through which the pin 36 is adapted to pass. The opening 40 is slightly larger than the pin 37 so that the element 37 has a working fit thereon. Between the webs 38 the forward side of the sleeve 39 is made rectangular in cross-section so as to provide a flat forward face 41 of substantial extent and a lesser flat underface 42. The webs 38 converge forwardly and at their forward 25 ends terminate in upturned hook portions 43. The forward ends of the webs 38 are connected by a web 44 which extends along the inner edges of the hook portions 43 providing a substantially vertical surface 45. Below the hook portion 43 30 the web 44 extends obliquely downwards and rearwardly, thus connecting the webs 38 together in the form of an integral unit. The latter portion of the web 44 is provided with an upwardly projecting stub which provides an upwardly directed horizontal face 46. At intermediate points each of the webs 38 is provided with an outwardly directed ear 47, which slopes forwardly and downwardly as shown in Fig. 7.

Referring more particularly to Fig. 4 it will 40 be seen that in the lower load bearing portion of the truck the ears 47 engage the forward faces of the arms 28 upon which the truss member 37 is mounted, and this engagement supports the truss member 37 so as to hold its contacting surfaces 45 and 46 in contact with the surfaces 41 and 42 respectively of the next adjacent truss element 37 in the forward direction. It will be 45 seen in Fig. 4 that any force applied to an intermediate link element will tend to effect rotation between adjacent link elements which would bring the upper ends of their arms 28 further apart. Such movement is resisted by the truss elements 37.

As will be seen from Fig. 6 the forward end 55 of the truss element 37 is relatively narrow so that it may be readily accommodated within the space between the webs 38 of the adjacent element 37. The assembly relation is shown in the left-hand side of Fig. 3. It will readily be understood that the pins 36 can be driven during the assembly of the track so as to locate the series of truss elements 37 in cooperating relationship, or they may be driven at any time and the truss members 37 and pins 36 may be removed 60 and replaced at any time without disassembling the remainder of the track. When the track folds up to go around the wheels 15 the ears 47 go into engagement with the arms 28 of the link element on which they are mounted and of the adjacent link element in the manner shown in Fig. 1. The ears 47 taper downwardly somewhat so as to make the desired contact. As a 65 result of this contact the track folds up in an orderly and regular manner.

In the structure of track described the pivots between the link elements 16 are very completely enclosed and are subject to very little wear. The principal wear is consequently limited to the 5 contacting surfaces of the truss elements 38. It will be seen that the wearing contact takes place exclusively at the engaging surfaces of the truss elements and these surfaces are made of substantial area so as to lessen wear. Consequently 10 by merely removing the pins 36 and replacing the truss elements 37 the worn surfaces are removed and the track is thoroughly reconditioned.

In the modified form of truss element shown in Figs. 9 and 10 the sleeve 39 is replaced by a 15 pair of bosses 48 which are integral with the webs 38. The forward ends of the webs 38 and the web 44 are configured so as to provide a concave surface 49 of cylindrical form which is adapted to engage that portion of the pin 36 20 of the adjacent truss element which is exposed between the bosses 48. With this modification the principal wear is between the surfaces 49 of the truss members 37 and the pins 36. Consequently the track can be substantially reconditioned by merely removing and replacing the pins 25 36 and truss elements 37.

Although the invention has been described in connection with the specific details of preferred embodiments thereof, it must be understood that 30 such details are not intended to be limitative of the invention except in so far as set forth in the accompanying claims.

Having thus described my invention, what I 35 claim as new and desire to secure by Letters Patent of the United States is:

1. A track comprising a series of track elements pivotally connected together, each track element comprising a pair of truss arms, a pin in the upper ends of each pair of truss arms, a 40 truss element having spaced bosses provided with openings whereby it is pivotally mounted on said pin leaving an intermediate portion of the pin exposed, said truss element being provided with a hook portion recessed to receive said intermediate portion of the pin of the adjacent track element between the bosses of its truss element, so as to truss the track against inward displacement.

2. A track element comprising a shoe plate, 50 a pair of link elements removably secured to said plate, a truss arm carried by each of said link elements, means adapted to provide pivotal connection with adjacent track elements and having a pressed fit in the link elements securing opposite pairs rigidly together, means having a 55 pressed fit securing the truss arms rigidly together and a hooked truss element pivotally carried by the last said pressed means.

3. A track comprising a series of track elements, each element comprising a shoe plate, a 60 pair of link elements bolted thereto, each element carrying a truss arm extending inwardly, a pin and sleeve pressed into said link elements to connect them rigidly together and provide pivoting

members for connecting the track element to adjacent track elements, a pin pressed into said truss arms, a truss element pivotally mounted on the track element by said pin, said truss element extending longitudinally with respect to the 5 track element and tapering away from said pin, its remote end being provided with a hook.

4. A track comprising a series of track elements, each element comprising a shoe plate, a 10 pair of link elements bolted thereto, each element carrying a truss arm extending inwardly, a pin and sleeve pressed into said link elements to connect them rigidly together and provide pivoting members for connecting the track element to adjacent track elements, a pin pressed into said truss 15 arms, a truss element pivotally mounted on the track element by said pin leaving an intermediate portion of said pin exposed, said truss element extending longitudinally with respect to the track element and tapering away from said pin, its remote end being provided with a hook recessed to receive the intermediate portion of the pin of the adjacent track element, and ears extending outwardly from said truss element adapted to engage the truss arms.

25 5. A truss element comprising a pair of bosses, convergent webs extending therefrom, a transverse web between the convergent webs connecting same at their adjacent ends, said webs being configured to provide a cylindrical bearing surface of substantially the same curvature as the 30 openings in the bosses, the first said webs being provided with outwardly projecting ears adapted to serve as abutment and spacing members.

6. A track comprising a series of track elements 35 pivotally connected together, each track element comprising a pair of truss arms, a pin fitted into the upper end of each pair of truss arms, a truss element for each track element comprising a pair of spaced bosses pivotally mounted on each pin, 40 a pair of convergent webs extending from said bosses and united at the opposite ends and formed into a hook having a cylindrical bearing surface of the same curvature as the pins, the bosses of each truss element being spaced apart a distance 45 to permit the hooked end of one truss element to engage the pin of an adjacent track element intermediate said bosses.

7. A truss element adapted for use with a series 50 of track elements pivotally connected together and each track element having a pair of truss arms connected by a transversely extending pin, comprising a pair of spaced bosses having bearing openings adapted for pivotal mounting on said pin, a pair of convergent webs extending from 55 said bosses and united at the opposite ends and formed into a hook having a cylindrical bearing surface of the same curvature as the bearing openings in said bosses, said bosses being spaced a distance to permit the hooked end of an adjacent truss element to engage the pin on which 60 said bosses are pivotally mounted.

JOSEPH KUCHAR.
